(57) **CLAIM**

The ornamental design for a load binder with a removable handle, as shown and described.

DESCRIPTION

FIG. 1 is a top perspective view of the load binder with a removable handle showing our new design;

FIG. 2 is a bottom perspective view thereof;

FIG. 3 is a front view thereof;

FIG. 4 is a rear view thereof;

FIG. 5 is a left view thereof;

FIG. 6 is a right view thereof;

FIG. 7 is a top view thereof; and,

FIG. 8 is a bottom view thereof.

The broken line showing of the handle in FIGS. 1-6 and FIG. 8 is included for the purpose of showing environmental structure and forms no part of the claimed design.

1 Claim, 8 Drawing Sheets

FIG. 1

FIG. 2

FIG. 3

FIG. 4

FIG. 5
